UNITED STATES PATENT OFFICE

2,056,700

OIL BURNER

George C. Way, Fairfax, Ohio, assignor of one-twelfth to James Utterbach, Madisonville, Ohio, and one-twelfth to William H. Dees, London, Ky.

Application April 2, 1935, Serial No. 14,307

1 Claim. (Cl. 158—53)

This invention I am about to describe has for an object to produce a burner of the type employing a liquid fuel of the character of crude oil such as petroleum and the like, in which certain volatile elements are present, capable of distillation therefrom upon the application of heat thereto, with a resultant residue of the nature of a highly carbonized by-product of non-volatile quality.

10 A further object is to produce a burner for crude oil and similar fuel in which marked simplicity of construction and operation is obtained as compared with other burners known to me.

These and other objects are attained in the 15 burner described in the following specification and illustrated in the accompanying drawing, in which:

Fig. 1 is a plan view of the burner embodying my invention.

20 Fig. 2 is a sectional view taken on the line 2—2 of Fig. 1.

Fig. 3 is a sectional view taken on the line 3—3 of Fig. 2.

Fig. 4 is a fragmental sectional view taken on the line 4—4 of Fig. 1.

25 The burner I have shown consists of a pan 11 which is provided with a rim 12, a central opening 13 which is flanged as shown at 14, an oil entrance opening 15, a gas exit opening 16, residue discharge openings 17 and 18, openings 19 and 20 which communicate through passage 21, a priming opening 22, a heating dome 23 which covers openings 15, 17 and 19, a heating dome 24 which covers openings 16, 18 and 20, a burner 25 which is mounted in flange 14 of opening 13, and a gas jet 26 which connects with gas exit 16 and discharges into opening 13.

30 Domes 23 and 24 covering openings 15, 17, 19, 16, 18 and 20, are sealed to the pan 11 at their lower edges by bolts 27. The pan, because of its rim 12 and opening flange 14, may receive and retain a wicking 28 preferably of incombustible characteristics, such as asbestos, by means of which oil entering the pan through opening 22 35 will fill the pan and become absorbed by the wicking so as to permit of its being lighted for initial heating of the burner domes, whereby gas generation will start.

The openings 15, 16, 19, and 20 are provided 40 with short pipe lengths which extend upwardly into the domes 23 and 24, the respective pipes 15' and 20' of the openings 15 and 20 being shorter than the respective pipes 16' and 19' in open-

ings 16 and 19, whereby inlet of oil through opening 15 will permit of a normal oil level of the height of the shorter pipe 15' being maintained, somewhat as shown at oil level 29 in Fig. 2, the higher pipe 19' in opening 19 carrying off the vapor and unvaporized oil into passage 21, thence upwardly through the shorter tube 20' in opening 20, such unvaporized oil also passing over with the vapor and possibly gradually accumulating until a normal level may be as shown at 30 is attained, the gas therefrom passing off through the higher pipe 16' of opening 16, thence through the jet 26 and upwardly for discharge from the orifices of burner 25, at which point the gas may be ignited and the resultant flame caused to impinge 10 on the walls at the tops of the domes.

Obviously, the heated domes create gasification of the oil within them, initial gasification taking place in dome 23 and final gasification taking place in dome 24.

20 The residue in the oil within the domes gradually becomes such that no volatile part remains and the mass of the residue has become highly impregnated with carbon. It is essential that provision be made for removal of this carbonized, 25 nonvolatile residue. For this purpose the openings 17 and 18, with their attached pipes are provided. A small feature which I have added, so that the valve control on the pipes openings 17 and 18 may not be the only means for preventing oil 30 escaping and also so that automatic closure when all residue has been drained from the domes, may be effected, is the ball valve 31 of opening 17 and ball valve 32 of opening 18.

Having thus described my invention what I 35 claim is:

An oil burner comprising a priming pan, a heating dome covering and sealing off a portion of said pan at each end thereof, a burner located on the pan between the domes and designed to direct 40 its flames against the domes, each of said sealed off portions having an inlet and an outlet, the outlet of one dome connecting with the inlet of the other dome, the inlet of said one dome connecting with a source of oil supply, the outlet of 45 the other dome connecting with the burner, said inlets extending within the domes to lower elevations than do the outlets therein, said pan outside the domes having an oil inlet for preliminary heating purposes, said dome-sealed portions of the 50 pan having drainage openings therein, and means to close or open said openings as required.

GEORGE C. WAY.
